MEANS FOR FEEDING WASHERS TO THE PINS OF MOLDS

Carlos Hall and Fernando Hall, Mexico, D. F., Mexico, assignors of one-third to Harry H. Hallett, Mexico, D. F., Mexico

Application October 28, 1937, Serial No. 171,572
In Mexico April 9, 1937

2 Claims. (Cl. 18—1)

This invention relates to means for feeding washers to the pins of molds employed in the manufacture of rubber heels, and it consists in the constructions, arrangements, and combinations herein described and claimed.

It is an object of the invention to provide a washer feeding device of simplicity in construction and operation and one in which the washers are fed to the pins of a mold regardless of the varying height of the pins as well as varying inclinations which the pins may have.

It is a still further object of the invention to provide a washer feeding device in which a washer magazine is provided, and in which the washers are individually placed in position upon the pins.

Additional objects, advantages and features of invention will be apparent from the following description considered in conjunction with the accompanying drawing, wherein

Figure 1 is a vertical sectional view through the washer feeding device.

Figure 2 is a fragmentary sectional view of the device in use.

Figure 3 is a fragmentary plan view of a series of molds indicating the positions of the pins.

Figure 4 is a front elevation of the magazine and feed guide.

Figure 5 is a rear elevation thereof.

Figure 6 is a bottom plan view of the guide.

There is illustrated in Figures 1 and 2, a tool generally indicated at 10, comprising an angularly disposed handle 11, the lower end of which mounts a guide block 12. Upon the underside of the handle 11 there is screw-threadedly engaged a shank 13, extending substantially at right angles to the handle, and upon the shank there is revoluble a hand grip 14. In order that the hand grip 14 may be free of vibrations and have the necessary flexibility, the grip has an axial bore 15 within which a piston 16 is reciprocable, the latter being secured to the shank 13 adjacent its lower end. A helical spring 17 is interposed between the piston and a washer 18 seated upon the base of the bore. From the foregoing, it will be seen that the hand grip is resiliently mounted and free from undue vibrations or shocks which might be imparted due to encountering pins of the molds, as will be more clearly apparent as the description proceeds.

The guide 12 has an aperture 19 extended vertically therefrom and fixed securely therein, there is a tubular sleeve 20, adapted to receive a tubular magazine sleeve 21. The sleeve 21 is open at its upper end to receive washers 22 arranged in superposed relation, as may be seen in Figure 2, retained in such position by engagement of the lowermost washer upon a ledge 23. As may be seen in Figure 6, the ledge is bifurcated

by a slot 24, permitting passage of the upper ends of pins 25 and preferably the ledge 23 is of a height permitting the pins to project thereabove so as to engage the apertures of the washers when drawn thereacross.

The guide 12 comprises an entrance opening 27 at its rear face, tapering in the direction of the bifurcation 24 serving to guide the pins so as to align the upper ends of the pins with the apertures of the washers. The front end of the guide 12 has a transversely extended slot 28 of a diameter to permit passage of the washers therethrough and the upper edge of the slot may be recessed as at 29 to permit passage of the upper ends of the pins therethrough.

In use, with the pins 25 arranged within the heel molds indicated at 30 in Figure 3, the device is grasped by the handle 14, the guide 12 being aligned with the rows of pins 25 so as to admit the pins through the entrance opening 27. The device will be held in the position shown in Figure 2, and obviously, the upper end of the pins will be guided by the bifurcation 24 so as to encounter the aperture of the lowermost washer within the magazine 21. The contact between the pins and washers will be more or less abrupt to effect withdrawal of the washers, but shock or unsteady effect will not be imparted to the operator due to the resilient hand-grip mounting.

While we have shown and described a preferred form of the invention, this is by way of illustration only, and we consider as our own, all such modifications in structure as fairly fall within the scope of the appended claims.

We claim:—

1. A washer feeding device for pins of molds comprising a body member having a pin entrance slot extending longitudinally thereof and opening upon the bottom wall thereof, said body having a vertically extended opening, a ledge on the body member beneath the opening, said ledge having a furcation extended in the direction of the slot and opening thereupon, a sleeve fixed in the vertical bore, a washer magazine engaged within the sleeve for discharge of washers upon the ledge, the sides of the entrance slot of the guide tapering in the direction of the ledge, a handle on the body member extending rearwardly of the entrance slot, the handle having a downwardly extending spindle, and a resiliently mounted hand grip on the spindle.

2. The structure of claim 1 in which the hand grip includes a bore, a piston fixed to the spindle adjacent the free end and reciprocable therein, and a helical spring on the spindle interposed between the piston and the base of the bore.

CARLOS HALL.
FERNANDO HALL.
